DESIGN FOR A TABLE

Edward G. Rudman, Nashua, and Francis G. Ranney, Hudson, N. H.

Application December 26, 1939, Serial No. 89,133

Term of patent 3½ years

To all whom it may concern:

Be it known that we, Edward G. Rudman, a citizen of the United States and resident of Nashua, in the county of Hillsborough, State of New Hampshire, and Francis G. Ranney, a citizen of the United States and resident of Hudson, in the county of Hillsborough, State of New Hampshire, have invented a new, original, and ornamental Design for a Table, of which the following is a specification, reference being had to the accompanying drawing, forming part thereof.

The figure is a view in perspective of a table, showing our new design.

We claim:

The ornamental design for a table, as shown.

EDWARD G. RUDMAN.
FRANCIS G. RANNEY.
